UNITED STATES PATENT OFFICE.

JOHN F. MORRISON, OF GLENDALE, NEW YORK.

CASTING MACHINE.

Application filed January 4, 1922. Serial No. 527,016.

To all whom it may concern:

Be it known that I, JOHN F. MORRISON, a citizen of the United States, residing at Glendale, Long Island, New York, have 5 invented new and useful Improvements in Casting Machines, of which the following is a specification.

This invention relates to casting machines and more particularly to centrifugal 10 casting machines and spouts for feeding centrifugal casting machines.

One of the objects of the present invention is to provide a simple and practical spout for feeding horizontally disposed cen- 15 trifugal casting machines, which spout will evenly distribute the molten metal to the interior of the mold.

A further object is to provide a spout which may be easily and quickly moved into 20 and out of operative relation with the mold and protect the workmen from the splash of molten metal.

Other objects will be in part obvious and in part hereinafter pointed out in connection with the accompanying sheets of drawings illustrating a preferred embodiment of 25 the present invention.

In these drawings wherein similar reference characters denote corresponding 30 parts,

Figure 1 is an elevational, sectional view of such parts of the apparatus as are necessary to understand the invention and,

Figure 2 is a sectional plan view thereof.

Referring to the drawings in detail and more particularly to Figure 1, 5 denotes a portion of the horizontally disposed rotating drum of a centrifugal casting machine. This drum is provided with an opening 6 through which is adapted to pass a spout 7. This spout 7 has a laterally extending horizontal opening 8 and communicates with a funnel-like portion 10 mounted upon a base 11 which in turn is carried by a movable support 12. Between the parts 45 7 and 10 is interposed a thick curved splash guard 13 having a reversely curved part 14. In operation the movable support 12 is rolled up to the casting machine with the part 7 extending in through the opening 6 and the guard plate 13 completely surrounding the end of the casting drum. The molten metal is then poured into the hopper or funnel 10 and flows inwardly

and then laterally outward in a flat even 55 sheet to the interior of the drum.

It will, of course, be understood that the drum is rotating at a high rate of speed while this is being done and were it not for the curved splash guard 13 the molten metal 60 would probably flow out through the open end to the injury of adjacent workmen.

A further statement of the operation is thought to be unnecessary, as the construction and method of use will be well understood 65 from the above disclosure by those skilled in the art.

Without further analysis, the foregoing will so fully reveal the gist of this invention that others can by applying current 70 knowledge readily adapt it for various applications without omitting certain features that, from the standpoint of the prior art, fairly constitute essential characteristics of the generic or specific aspects of this invention, and, therefore, such adaptations should 75 and are intended to be comprehended within the meaning and range of equivalency of the following claims.

What I claim is:—

1. A spout for use in centrifugal casting machines having a movable base, a hopper, a horizontal elongated portion connected with said hopper, said last mentioned portion having a horizontally disposed elongated opening out through which the molten metal is adapted to pass.

2. A spout for use in centrifugal casting machines having a movable base, a hopper, a horizontal elongated portion connected with said hopper, said last mentioned portion having a horizontally disposed elongated opening out through which the molten metal is adapted to pass and a splash guard 85 associated with said spout.

3. A spout for use in centrifugal casting machines having a movable base, a hopper, a horizontal elongated portion connected with said hopper, said last mentioned portion having a horizontally disposed elongated opening out through which the molten metal is adapted to pass and a splash guard 100 interposed between the funnel and the horizontal part adapted to fit over the end of the casting drum.

Signed at Brooklyn, N. Y., this 10th day of October, 1921.

JOHN F. MORRISON.
